United States Patent Office

Des. 203,270
Patented Dec. 21, 1965

203,270

BINDING POST OR SIMILAR ARTICLE

Dennis William Bell, 34 Chertsey Rise,
Stevenage, England

Filed Nov. 3, 1964, Ser. No. 82,453

Term of patent 7 years

(Cl. D26—1)

FIG. 1 is a front elevational view of a binding post or similar article, showing my new design;

FIG. 2 is a side elevational view thereof;

FIG. 3 is a top plan view thereof; and

FIG. 4 is a bottom plan view thereof.

I claim:

The ornamental design for a binding post or similar article, as shown.
